Specification for Design.

Patented July 29, 1919.

Application filed March 14, 1919. Serial No. 282,755. Term of patent 14 years.

To all whom it may concern:

Be it known that I, JOHN H. KOHSIEK, a subject of the Queen of Holland, residing at Kenmore, in the county of Summit, State of Ohio, have invented a new, original, and ornamental Design for Pneumatic Tires, of which the following is a specification, reference being had to the accompanying drawings, forming a part thereof.

In the drawings, Figure 1 is a plan view of a portion of a tire showing my new design.

Fig. 2 is a cross section on the line 2—2 of Fig. 1.

I claim:

The ornamental design for a pneumatic tire as shown.

JOHN H. KOHSIEK.
